(57) **CLAIM**

I claim the ornamental design for the non-peep bowsight for archery, as shown and described.

DESCRIPTION

FIG. 1 is a top view of the first embodiment of the non-peep bowsight for archery;

FIG. 2 is a bottom view of the first embodiment of the non-peep bowsight for archery;

FIG. 3 is a top view of the second embodiment of the non-peep bowsight for archery;

FIG. 4 is a bottom view of the second embodiment of the non-peep bowsight archery;

FIG. 5 is a top view of the third embodiment of the non-peep bowsight for archery;

FIG. 6 is a bottom view of the third embodiment of the non-peep bowsight for archery;

FIG. 7 is a front side view and a rear side view of all three embodiments of the non-peep bow bowsight for archery,

FIG. 8 is a left side view of all three embodiments of the non-peep bowsight for archery,

FIG. 9 is a right side view of all three embodiments of the non-peep bowsight for archery; and,

FIG. 10 is an environmental perspective view of the first embodiment of the non-peep bowsight for archery, the dashed lines forming no part of the claimed design.
